No. 5, & 19.

Dec. 12, 1871.

UNITED STATES PATENT OFFICE.

ARCHIBALD McCALLUM, OF HALIFAX, ENGLAND, ASSIGNOR TO JOSEPH WILD & CO., OF NEW YORK CITY.

DESIGN FOR A CARPET-PATTERN.

Specification forming part of Design No. 5,419, dated December 12, 1871.

To all whom it may concern:

Be it known that I, ARCHIBALD McCALLUM, of Halifax, in the county of York, England, have invented a new and original Design for a Carpet, of which the following is a specification:

In the drawing, a represents ground figures b, b and c c c, respectively, arranged on the edges thereof in such a way that, if jointed by connecting lines, two triangles, crossing each other, will be found.

The nature of my design is fully represented in the accompanying photographic illustration, to which reference is made.

I claim as my invention—

The design for a carpet, as shown.

ARCHIBALD McCALLUM.
